CLOCKFACE

Thomas D. Di Addario, Buffalo, N. Y.

Application March 2, 1948, Serial No. 144,863

Term of patent 3½ years

(Cl. D42—10)

To all whom it may concern:

Be it known that I, Thomas D. Di Addario, a citizen of the United States, residing at Buffalo, in the county of Erie, State of New York, have invented a new, original, and ornamental Design for a Clockface, of which the following is a specification, reference being had to the accompanying drawing, forming part thereof.

The figure is a front elevational view of a clockface showing my new design, the same being of no substantial thickness.

I claim:

The ornamental design for a clockface, as shown and described.

THOMAS D. DI ADDARIO.
